INDIVIDUAL CARD PLAYER'S TRAY

Elsworth W. Gardenhire, North Sacramento,
Calif.

Application June 1, 1948, Serial No. 146,716

Term of patent 3½ years

(Cl. D34—13)

To all whom it may concern:

Be it known that I, Elsworth W. Gardenhire, a citizen of the United States, residing at North Sacramento, in the county of Sacramento and State of California, have invented a new, original, and ornamental Design for Individual Card Player's Tray, of which the following is a specification, reference being had to the accompanying drawing, forming a part thereof.

I claim:

The ornamental design for an individual card player's tray, as shown.

ELSWORTH W. GARDENHIRE.
